UNITED STATES PATENT OFFICE

DANA E. WEScott, OF SOUTH BEND, INDIANA.

ELECTRIC-LIGHTING SYSTEM.

1,301,206.

Specification of Letters Patent. Patented Apr. 22, 1919.

Application filed March 31, 1916. Serial No. 88,125.

To all whom it may concern:

Be it known that I, DANA E. WEScott, citizen of the United States of America, residing at #729 So. Michigan street, South Bend, in the county of St. Joseph and State of Indiana, have invented certain new and useful Improvements in Electric-Lighting Systems, of which the following is a specification.

10 This invention relates to electric lighting systems, and has for its particular object, to provide means whereby a plurality of lamp circuits can be controlled from a central station to extinguish the lamps in all of said 15 circuits simultaneously, or to extinguish the lamps in certain circuits at a different interval of time from the remaining circuits.

This invention is particularly adapted for use in connection with an arc-lamp or constant current circuit and which is connected to control a plurality of auxiliary incandescent lamp circuits which are required to be extinguished separately and at predetermined times.

20 25 These and other objects hereinafter described, are attained by the means illustrated in the accompanying drawings, in which:

Figure 1 is a diagrammatic view showing two auxiliary lamp circuits connected to an arc-lamp circuit.

Fig. 2 is a side elevation of a portion of a cut-out shown in Fig. 1.

Fig. 3 is a detail perspective view of the lower end of the operating rod shown in 30 Figs. 1 and 2.

Fig. 4 is a view in elevation of the toothed member of the cut-out shown in flattened condition.

Fig. 5 is a perspective view of a modified 40 form of solenoid member, and

Fig. 6 is a diagrammatic view showing a three way circuit.

Similar reference numerals in all of the figures of the drawings designate like parts.

45 Referring to the drawings, 5 designates an arc-lamp circuit having a generator 6 of the usual type, and the arc-lamps 7, connected in series and indicated diagrammatically, and a switch 8.

50 Connected in series with the circuit 5, are the solenoid magnets 9 which serve to control the movements of the double core 10 and which carries the contact-plate 11. The ends of this plate 11 are adapted to engage with the stationary contacts 12 to close a primary or transformer circuit 13, to which

power is supplied by a generator of any well known type and which is not shown in the drawings. From the above description, it will be seen, that the opening of the switch 60 8 will demagnetize the magnets 9, which will allow the core 10 and the plate 11 to fall and break the connections of the primary circuit.

As shown in the drawing, there is also 65 connected in series with the circuit 5 another pair of solenoid magnets 14 which control a double core 15, and the same carries a contact plate 16, whose ends engage the stationary contacts 17 to close the auxiliary incandescent lamp circuits 18 and 19 and which receive power through the transformers 20 and 21 from the primary circuit 13. The incandescent lamps 23 of these circuits are connected in multiple therewith.

75 It being desirous in this system to extinguish permanently one circuit of incandescent lamps before the other set, in this case the lamps 23, a cut-out is provided which is constructed as follows: Contact plate 16 is 80 provided on its upper side with an insulating block 24 provided with a central aperture through which passes a rod 25 and which also passes through an aperture in said contact plate 16. Said rod is provided 85 with a head 26 which is larger than the aperture in block 24 and by which the rod is suspended. The lower end of the rod is provided with a cross-arm 27 which is adapted to engage the edges of the teeth 28 and 29 in the cylindrical members 30 and 31 to rotate said rod and arm. These cylindrical members are supported in a suitable frame 32 and said rod 25 passes freely through said members 30 and 31, and which are spaced 95 apart with their teeth disposed opposite each other. The cross-arm is positioned between said members 30 and 31 from one member to the other. The teeth of the member 30 are formed with notches of equal 100 depth between them, and those of the member 31, are formed with alternate deep and shallow notches, as clearly shown in Fig. 4 of the drawings, and the teeth of one member are staggered relatively to the teeth of 105 the other set.

Thus it will be seen, that when the cross-arm 27 drops downwardly from a deep notch in the member 31, as shown in Fig. 3, it engages an inclined edge of a tooth in the 110 member 30, which forces it sidewise in its course to the bottom of the notch and con-

sequently rotates the rod 25 beyond the vertical alinement of the next tooth in the member 31, so that, in moving upwardly it will engage the inclined edge of said tooth, which 5 will guide it into the next notch and in position to engage another tooth in the member 30 when it again descends.

The contact plates 11 and 16 are resiliently supported from the cores 10 and 15 respectively, they being supported on springs 33 which are in turn supported on nuts 34 adjustably secured on the lower ends of the suspension rods 35 and are secured in any desired manner to the cores 10 and 15. 10 These suspension rods 35 of each core are preferably positioned one on each side of the rod 25 and pass freely through apertures in the blocks 24 and the contact plates, and it is understood, that when a double pole switch 15 is used, none of the several parts of the cut-out mechanism are ever in electric contact with the contact plates. By supporting the plates 11 and 16 in the manner described, it is obvious that the cores can move a slight 20 distance independently of the contact plates, so that any slight variation in the voltage of the arc circuit, will not disturb the engagement between the plates 11 and 15 and their contacts, thereby furnishing to the 25 lamps 23 and 24 an even power which will give a steady light.

As shown in the drawings, circuits 18 and 19 are formed with three wires, one wire 36 being common to both circuits and together with a wire 37 forms the circuit 19 and is connected to the terminals of one member 37' of the transformer 21, and the remaining wire 38 of the circuit 18 is connected to one of the fixed contacts 17 which 40 is engaged by one of the terminals of the plate 16. The opposite contact 17 is connected to one terminal of another member 39 of the transformer 21, the other end of said member 39 being connected to the same terminal of the member 37' as is the wire 36. Thus the transformer member 39 is connected in circuit 18 and the member 37' is connected in the circuit 19.

Assuming that the parts are positioned as 50 shown in Fig. 1, the lamps in all of the circuits are lighted. It now being desirous of extinguishing the lamps 23 in circuit 18 and keep them unlighted while the lamps in the circuit 19 are lighted, the operator at the central station of the arc circuit will momentarily open the switch 8 which will break the circuit 13 at the contacts 12 and shut off the current furnished to the circuits 18 and 19 and consequently cut out all of the lamps in 55 both of the circuits. At the same time it is obvious that the arc-lamps will also be extinguished. Simultaneously the magnets 14 are deenergized thereby allowing the core 15, plate 16, and rod 25 to descend, which 60 will cause the cross-arm to descend from

one of the deep notches in member 31, as at 41 in Fig. 2, to the inclined edge of the tooth 42 in the member 30, which will direct it downwardly on an incline to the bottom of the notch and consequently rotate the rod 70 25. Immediately the operator returns the switch to a closed position, which will at once energize the magnets 9 and 14, and their cores will be drawn upwardly. The upward movement of the core 10 will close 75 the circuit 13 at the contacts 12. At the same time, the core 15 will ascend together with the plate 16, rod 25 and its cross-arm 27, but said cross-arm in moving upward from the notch of the tooth 42 will engage 80 the inclined edge of the tooth 43 in the member 31 and be directed into the shallow notch of that tooth. This will limit the upward movement of the plate 16 and rod 25, and consequently prevent the ends of the 85 plate 16 from engaging with the contacts 17 and thus keeping the circuit 18 open with its lamps 23 unlighted. The circuit 19 is not affected by the open circuit 18 and will receive current through the transformer from 90 the circuit 13, and its lamps will remain lighted as long as the circuit 13 is closed.

Should the member 31 be constructed with the deep and shallow notches, as shown in the drawings, another opening and closing of the switch 8, will rotate the cross-arm in the next deep notch and this will close the 95 circuit 18 again and its lamps will be lighted.

It will be understood that the deep and shallow notches in the member 31 can be arranged in any suitable combination to control any number of auxiliary circuits as desired.

It will be observed, that in this system a constant current circuit is used as a control or master circuit for a plurality of auxiliary incandescent circuits which can be extinguished separately and at different times of the day or night, and all can be controlled by an operator located at the station. It is further evident, that various uses and combinations can be made with this system, and it will be seen, that when the switch of the arc-circuit is thrown open, the primary or transformer circuit will be cut 100 out and remain so during the time the arc-circuit is idle, thus saving the leakage loss in the primary circuit during the inactive 105 part of the day.

The solenoid member shown in Fig. 5 is 110 provided with a contact plate 42' mounted in each end of the supporting bar 43' and projecting to both sides thereof, forming a double pole switch in contradistinction to the type shown in Fig. 1, wherein the contact 115 plate 11 is secured longitudinally of the support, making a single pole switch.

In Fig. 6 it will be observed, that when the cut-out operates to disconnect the wire 38 and the member 39, it will extinguish the 120 125 130

lamps in both circuits 44 and 45, which are duplicates of the circuit 18 in Fig. 1.

It is obvious that the master circuit may be varied at the station by either short circuiting the dynamo, lowering the quantity of current in the circuit, or opening the circuit momentarily through the switch.

Having thus fully described the invention, what is claimed is:

- 10 1. An electric lighting system, comprising a constant current circuit, a primary circuit, means responsive to the condition of the constant current circuit for controlling the primary circuit, a plurality of lamp circuits arranged to derive power from the primary circuit, and a circuiting means for certain of the lamp circuits responsive for circuiting purposes to alternate energizations only of the constant current circuit.
- 20 2. An electric lighting system, comprising a constant current circuit, a primary circuit, means responsive to the energization and de-energization of the constant current circuit for controlling the primary circuit, a plurality of lamp circuits deriving power from the primary circuit, and means whereby certain of the lamp circuits may be de-energized through de-energization of the constant current circuit and maintained de-energized throughout a predetermined number of energizations and de-energizations of the constant current circuit.
- 30 3. An electric lighting system, comprising a constant current circuit, a plurality of lamp circuits, a means directly responsive to

each energization and de-energization of the constant current circuit for making and breaking certain of the lamp circuits, and another means responsive to said conditions of the constant current circuit for making 40 and breaking the remaining lamp circuits only through a predetermined number of energizations and de-energizations of the constant circuit.

4. An electric lighting system, comprising 45 a constant current circuit, a switch for controlling the energization of such circuit, a plurality of lamp circuits, means directly responsive to each actuation of said switch for controlling certain of the lamp circuits, and 50 another means for certain other of the lamp circuits for operatively controlling said lamp circuits only following a predetermined number of operations of said switch.

5. An electric lighting system, comprising 55 a constant current circuit, a switch for opening and closing said circuit, a plurality of lamp circuits, means directly responsive to each operation of said switch for controlling certain of said lamp circuits, and a circuiting control means for the remaining lamp circuits responsive for circuiting purposes to alternate closing operations only of said switch.

In testimony whereof I affix my signature 65 in presence of two witnesses.

DANA E. WESCOTT.
